(57) **CLAIM**

The ornamental design for a face mask as shown and described.

DESCRIPTION

FIG. 1 is a front view of a face mask showing our new design;

FIG. 2 is a back view thereof;

FIG. 3 is a top view thereof, the bottom view being identical; FIG. 4 is a right side view thereof, the left side view being identical;

FIG. 5 is a perspective view of the face mask in an alternate position with environment;

FIG. 6 is a front view of FIG. 5;

FIG. 7 is a top view of FIG. 5; and,

FIG. 8 is a left side view of FIG. 5, the right side view being a mirror image.

In the drawings, the broken lines in FIGS. 1–4 depict elements of the face mask that form no part of the claimed design. The broken lines showing a hood in FIGS. 5–8 depict environmental matter and form no part of the claim. All broken lines form no part of the claim. The drawings are shaded to indicate contrasting surfaces.
